UNITED STATES PATENT OFFICE

2,579,460

NONREFILLABLE CONTAINER

Nicholas Archidiacano, Boston, Mass.

Application November 6, 1948, Serial No. 58,745

1 Claim. (Cl. 215—22)

1

This invention relates to a non-refillable attachment for permanent application to bottles and other vessels containing liquors, wines, perfumes or the like.

It is an object of the invention to provide a non-refillable attachment of the class described of simple, efficient and comparatively inexpensive construction and which can be readily fixed to the outlet end of the neck of a bottle and serve to prevent refilling of the latter when the original contents thereof is exhausted.

It is a further object of the invention to provide an attachment of the class described whose essential parts may be molded to size and shape from thermoplastic synthetic material, such as synthetic resin, which will not be chemically acted upon by the liquid contents of the bottle.

Attachments of the class referred to are usually constructed with a check valve which closes toward the interior of the container to which the attachment is applied and I have found that after pouring liquid from the container past this check valve, it frequently happened that a vacuum was created within the container sufficient to hold the check valve closed on its seat when attempting subsequently to again pour liquid from the container. It is therefore a further object of this invention to obviate the undesirable characteristic just referred to.

To these ends I have provided certain improvements in attachments of the class described as set forth in the following description, the several novel features of the invention being separately pointed out and defined in the claim at the close of said description.

In the accompanying drawings:

Figure 1 is a side elevation, partly in section, of an embodiment of the invention and provided with a valve dislodging ball as hereinafter described.

Figure 2 is a top plan view, partly broken away and in section, of the upper inverted cup-shaped weight-confining member hereinafter described.

Figure 3 is a side elevation of the member shown in Fig. 2.

Figure 4 is a section on line 4—4 of Fig. 2.

Figure 5 is a section on line 5—5 of Fig. 1.

Figure 6 is a sectional view of the upper portion of the bottle and its attachment occupying inverted pouring position.

In the accompanying drawings 1 represents the body of my improved attachment, said body being formed interiorly with a cylindrical chamber. At 2 is an upper inverted cup-shaped ball-confining lining member fitted within the body

2

1. At 3 is a lower cup-shaped ball-confining member that is also fitted within the body 1 immediately below the member 2. A valve 4 is slidably confined within the lower lining member 3 and a ball weight 5 disposed between the members 2 and 3 is normally seated upon the valve 4 to hold the same closed upon a valve seat provided by a re-entrant radial flange 31 provided at the lower end of lining member 3. The upper end of body 1 is normally closed by a removable cap 6. All of these parts, with the possible exception of the ball 5, are preferably produced from thermoplastic synthetic material such as synthetic resin. The ball 5 may also be produced from such material, but in practice I have utilized a stone sphere of substantial weight.

The lower cup-shaped lining member 3 comprises an interiorly and exteriorly cylindrical body portion to which the reference numeral 3 is applied, said body portion being made at its lower end with the re-entrant radial flange 31 whose top provides a seat for the valve 4, said flange surrounding and defining an outlet port 7.

The lower end portion of body 1 is interiorly threaded as at 8 and screwed upon the upper end of the neck 9 of a bottle holding the liquid that is to be dispensed, said neck being formed with screw threads 10 for engagement with the threads 8 of body 1. Preferably cement is provided between the neck 9 and body 1 as indicated at 11 to maintain a leak-proof joint between the two parts and also to permanently secure the body 1 in position on the neck of the bottle. Between the upper end of neck 9 and the bottom of lining member 3 I may provide a gasket annulus 12 of rubber, cork or the like.

The body portions of the lining members 2 and 3 are interiorly and exteriorly cylindrical and are fitted snugly chime-to-chime within body 1 where they are preferably permanently secured by means of cement. Thus these two elements 2 and 3 provide a ball-enclosing cage which provides for limited movement of valve 4 and ball 5 toward and from seat flange 31. As shown in Figs. 1 and 5 the valve element 4 is made at its periphery with a circular series of upstanding spaced apart lugs 13 slidably engaging the interior of the lining element 3, the arcuate spaces alternating with these lugs serving as passageways for the liquid discharged from neck 9 when the bottle is inverted after removal of cap 6.

Adjacent to its top the upper lining element 2 is made with a centrally disposed dome 15 connected by a circular series of radial spaced-apart

arms 16 with the cylindrical body portion of lining element 2 as shown particularly in Figs. 2, 3 and 4. This dome 15 is of less diameter than the interior of lining element 2 so that the spaces 17 between the arms 16 serve as passageways for the liquid during pouring operations.

When the bottle is inverted to pour liquid therefrom, the ball 5 is moved by gravity into the socket provided by dome 15 thus permitting the liquid to shift valve 4 away from its seat and to pass around the valve and ball 5 directly to the passageways 17 (Fig. 2) of lining member 2 which alternate with the arms 16 of lining member 2.

In order to prevent the introduction of a probe through passageways 17 by means of which to manipulate the valve 4 in an attempt to refill the bottle, the upper end of the lining element 2 is made with a circular series of spaced-apart radially disposed re-entrant baffle lugs 18 each of which is disposed directly opposite and above one of the passageways 17 with its inner end terminating in close proximity to the interior of the dome 15. The spaces between these baffle lugs serve as passageways for the liquid during pouring operations.

The upper end of the body 1 of the attachment is made with an outlet nipple 19 of reduced diameter that is exteriorly threaded to receive upon it the removable interiorly threaded cap 6.

When the parts 1, 2, 3, 4 and 6 are produced in molds from thermoplastic synthetic material of the kind referred to above they are, except perhaps for some snagging, in completed form ready for assembling and not subject to corrosion or chemical action by the liquid contents of the bottle or other container to which the attachment is applied.

In practice I have found that it sometimes happens that when a quantity of the contents of a non-refillable container is poured therefrom, a partial vacuum will be produced within the same with the result that the inwardly closing check valve will be held closed upon its seat and prevent a second pouring when the container is again inverted. To avoid this I provide within the bottle 9 a loose sphere 20 of stone, or other non-buoyant material, which will gravitate through the contents of the container when the latter is inverted and by striking against the valve 4 dislodge and open the same, as shown in

Fig. 6, should said valve be at such time held on its seat by outside atmospheric pressure. Fig. 6 of the drawing also shows that the sphere 20 is substantially smaller in diameter than the port 7 that is controlled by valve 4 so that it is not capable of closing said port.

What I claim is:

A container for liquids made with an outlet passage; a pair of cup-shaped lining members fitted and fixed within said passage one above the other with their chimes abutting thereby to provide between them an interiorly cylindrical chamber, the top wall of the upper member being made upon its lower side with a central socket surrounded by circular series of both axial and lateral passageways through which the contents of the container flows when the latter is inverted, and the bottom wall of the lower member being made with a re-entrant flange whose top side provides a seat for a check valve, said flange surrounding an outlet port; a check valve slidably fitted within said chamber for limited axial movement between said flange and said socket, the periphery of said check valve being made with outlet passageways for the liquid contents of said container; a gravity-influenced ball loosely mounted within said chamber and by which said check valve is normally held upon said seat, and a gravity-influenced non-buoyant ball of less diameter than the width of said outlet port and disposed within the body of the container and operable when the latter is inverted to engage and open the check valve while said first-mentioned ball is seated within said socket and said non-buoyant ball occupies said outlet port.

NICHOLAS ARCHIDIACANO.
